UNITED STATES PATENT OFFICE.

GRACE G. YOUNG, OF PHILADELPHIA, PENNSYLVANIA.

SHOE.

Application filed December 31, 1925. Serial No. 78,520.

My invention relates to low shoes, particularly to the type known as pumps or slippers. Many wearers of shoes of this type have found that either the one or the other 5 or both sides thereof, in the region of the instep, gape or flare away from either one or both sides of the foot. This causes the shoe to present a more or less unattractive and unsightly appearance.

10 The general object of the present invention is to provide means which is invisible when the shoe is upon the foot for correcting this defect and for causing the sides of the shoe to hug or fit closely against the 15 sides of the foot.

Another object of the invention is to provide novel means of the character indicated which is adapted to be readily and easily detached and removed from one shoe and 20 placed in another shoe, thereby rendering it unnecessary to possess any considerable number of such devices.

Other objects and advantages of the invention will be pointed out in the detailed 25 description thereof which follows or will be apparent from such description.

In order that the invention may be readily understood and its practical advantages 30 fully appreciated reference may be had to the accompanying drawing in which I have illustrated certain convenient forms of embodiment of the invention. However, it will be understood that the invention is susceptible 35 of embodiment in other forms of construction than those shown and that changes in the details of construction may be made within the scope of the claims without departing from the principle of the said invention.

40 In the drawing:

Fig. 1 is a perspective view of a shoe provided with a device embodying my invention also shown in perspective;

Fig. 2 is a view in perspective of one of 45 the elements included in the structure of the device shown in Fig. 1;

Fig. 3 is a view similar to that shown in Fig. 1 but showing a modified construction of device embodying the invention;

50 Fig. 4 is a similar view showing another modified form of construction of the device;

Fig. 5 is a view showing in detail a means for connecting the ends of tape employed in the construction of the device to portions 55 of the shoe; and

Fig. 6 is a view showing a modified construction of means for joining a plurality of tapes together at an intermediate point of the structure.

Referring to the drawing: 1 designates a 60 shoe of the type to and for which the invention is adapted. Referring first to Figs. 1, 4 and 5, it will be seen that the strips 65 of elastic material employed in the construction of devices embodying the invention are provided at their ends with fastening means 2 consisting of hooks of the character and construction best shown in Fig. 5. These hooks are provided with eyes 3 of oblong shape through which an end of a tape 70 may be inserted and turned down and sewed, as indicated at 4.

Referring now to Fig. 1 of the drawing, it will be noted that there are employed in the construction two strips 5 and 6. Each 75 of the strips is provided at its opposite ends with a fastening device 2. Each strip is also secured at its opposite ends to the same side of the shoe. The said strips extend through elongated eyes 7 of a connecting device 8. 80 The strips 5 and 6, which as stated are elastic, are held under slight tension when the shoe is off the foot. It will be noted that the rear end of the strip 5 is connected to the inner side of the upper of the shoe near 85 the upper edge thereof and at a point within the region of the instep portion thereof, while the opposite end of the said strip, which extends through an elongated eye 7 of the connecting device 8 located at about 90 the middle of the shoe, is connected to the upper of the shoe at a point located in a forward position from the connecting device 8 and at a point near the edge of the inner sole of the shoe. The elastic tape 6 is likewise connected to the opposite side of the shoe. 95

It will be apparent that upon placing a shoe upon a foot of a wearer the pressure of the foot upon the tapes 5 and 6 would 100 cause portions thereof to lie flat against the inner sole of the shoe and other portions thereof to lie against portions of the opposite sides of the upper of the shoe.

In the construction as shown in Fig. 3 of the drawing the tapes 10 and 11 of elastic material respectively extend diagonally across the shoe. One end of the tape 10 is connected at 12 to one side of the upper of the shoe at a point adjoining the upper edge 110

thereof within the region of the instep portion. The opposite end thereof is connected in the construction shown to the opposite side of the upper, as indicated at 13, at a 5 point forwardly with respect to that at which the upper end thereof is connected. The tape 11 is connected in a similar manner; that is to say, one end thereof is connected as indicated at 15 to one side of the 10 upper of the shoe near the upper edge thereof and within the instep portion, while the opposite end thereof is connected to the opposite side of the shoe, as indicated at 16, at a point near the edge of the inner sole 15 and also in forward position with respect to the point 15. The tapes 10 and 11 cross each other as shown and are connected together permanently by stitching as indicated at 17. Likewise the opposite ends of the tapes or 20 strips 10 and 11 are connected by stitching to the upper of the shoe. As in the case of the construction shown in Fig. 1, when the shoe is placed upon the foot portions of the tapes 10 and 11 are pressed flat against 25 the inner sole of the shoe and one end portion of each tape is located and held between the adjacent portions of the upper and adjoining portions of the instep portions of the foot. In both forms of construction 30 the tapes 5, 6, 10 and 11 operate, when the shoe provided with the same is upon a foot, to draw the opposite sides of the instep portion of the upper closely and snugly against the opposite sides of the foot 35 of the wearer thereby preventing gaping or flaring away of the instep portions of the upper, whereby the neatness of the shoe upon the foot is very greatly enhanced.

In the construction as shown in Fig. 6 of 40 the drawing the tapes 10' and 11' are not permanently fastened together at their middle portions as is the case in the construction as shown in Fig. 3 of the drawing, but the said tapes are interlocked with each 45 other by means of the open rectangular shaped member 20. It will be noted that the members 10' and 11' cross each other and that one of the tapes 10' passes above the member while the other of the said tapes passes underneath the same but over the 50 other of the said tapes. It will be apparent that the member 20 operates to slidably connect the tapes 10' and 11' together at their middle portions.

The construction as illustrated in Fig. 4 55 is intended for use in the case of shoes in which one side only of the instep portion of an upper gapes or flares away from the foot. In the said construction two tapes 60 are connected to form a device of Y-shape. One of the tapes 21 is connected by means of a hook 2 to one side of the instep portion of the upper at a point near its upper edge, while the opposite end thereof is connected 65 to the opposite side of the shoe, as indicated

at 22, and in forward relation with respect to the point of connection of the upper end thereof. The branch tape 23 is connected to the tape 21 near its middle portion and is extended from such point of connection to the same side of the upper of the shoe as that to which the upper end of the tape 21 is connected and is connected thereto at a point near the upper edge thereof, which point is located in front of the point of connection of the tape 21. 75

Upon the placing of a shoe provided with a device such as is shown in Fig. 4 upon the foot of a person the lower portions of the tapes 21 and 23, which are elastic, are 80 pressed down against the inner sole of the shoe while the upper portions thereof are held between the foot and the adjoining portion of the upper of the shoe. The tension exerted by the tapes 21 and 23 tends and operates to pull the upper inwardly to hold it closely and snugly against the adjoining instep portion of the foot thereby preventing the gaping or flaring away thereof. 85

In the several forms of construction the 90 tapes or strips of material employed are elastic so that upon the placing of a shoe provided with a device embodying my invention upon a foot the tapes thereof are subjected to extension and additional tension 95 whereby they operate to hold the upper portions of the instep portion of the upper snugly against the foot and accomplish the purpose desired by preventing the gaping or flaring away of the said portion. 100

It has been found in actual practice that the fastening connections, such as 2, the connection 8 for connecting the intermediate portions of the tapes 5 and 6 together, and the connection 20 for slidably connecting the tapes 10' and 11' together, do not interfere with the comfort of shoes when the same are worn. In other words, no discomfort to the wearer is caused by the employment of devices embodying my invention. 105

It will be seen that in the case of low 110 shoes which are lacking in neatness due to the gaping or the flaring of the instep portions of the uppers thereof away from the foot I am enabled by my invention to prevent such gaping or flaring and to cause such shoes to present a neat appearance by holding such portions of the uppers closely and snugly against the instep portion or portions of the foot. 115

Having thus described my invention, what I claim and desire to secure by Letters Patent is:

1. A device of the character described, 120 comprising an elastic strip of material having connection at one end with one side of the instep portion of the upper of a low shoe adjacent the top edge thereof, the said strip extending downwardly, forwardly and transversely of the said shoe and having 125

connection at its other end with the opposite side of the instep portion of the upper adjacent the bottom edge thereof.

2. A device of the character described, comprising a plurality of strips of elastic material each having connection at one end with the instep portion of the upper of a low shoe near the top edge of said portion, and each of the said strips extending forwardly and downwardly and having connection at its other end with the said shoe adjacent the bottom thereof, which strips are placed under tension by the presence of a foot in the shoe to pull the top edges of the instep portion of the upper toward the foot.

3. A device of the character described, comprising a plurality of strips of elastic material extending in cross-wise relation to each other, one end of each strip having connection with the instep portion of the upper of a low shoe at a point adjacent the upper edge thereof, and each of the said strips extending forwardly from such point of connection, and the opposite end of each of said strips having connection with the opposite side of the shoe at the bottom thereof.

4. A device of the character described,

comprising a plurality of strips of elastic material having connection with each other at points intermediate their ends, one end of each strip having connection with opposite sides of the instep portion of the upper of a low shoe and the opposite ends of each of said strips having connection with the said shoe at forward points thereof, the said points being located adjacent the bottom of the said shoe.

5. A device of the character described, comprising a plurality of strips of elastic material extending in cross-wise relation to each other, which strips are permanently connected together at intermediate points of their lengths, one end of each strip being connected to one side of the instep portion of the upper of a low shoe near its upper edge the points of connection being at opposite sides of the said upper, and the opposite ends of said strips being connected to opposite sides of the shoe at points near the bottom thereof and in forward relation to the other ends thereof.

In testimony that I claim the foregoing as my invention I have hereunto signed my name this 30th day of December, A. D., 1925.

GRACE G. YOUNG.
